UNITED STATES PATENT OFFICE.

WILLIAM A. KNIPE AND TIMOTHY MCKINNEY, OF WARD HILL, MASSACHUSETTS;
SAID MCKINNEY ASSIGNOR TO SAID KNIPE.

APPARATUS FOR TREATING BOX-TOE PIECES.

1,167,904.

Specification of Letters Patent. Patented Jan. 11, 1916.

Application filed December 21, 1914. Serial No. 878,280.

To all whom it may concern:

Be it known that we, WILLIAM A. KNIPE and TIMOTHY MCKINNEY, citizens of the United States, residing at Ward Hill, in 5 the county of Essex and State of Massachusetts, have invented an Improvement in Apparatus for Treating Box-Toe Pieces, of which the following is a specification.

In the manufacture of shoes having "cut-off" vamps to which a textile toe piece or "butter" is attached, it is desirable, as described in the patent to Knipe, No. 1,127,641, to saturate the portion of the piece within the line of attachment to the sole, with a 15 substance which is freely liquid when heated, and stiffens when cooled, leaving the edge portion beyond said line of attachment unsaturated, to obviate various objections which arise when the entire toe piece is saturated, such as the difficulty of securing a 20 firm hold thereon with the lasting pincers.

The object of our invention is to provide a simple and practical apparatus for saturating the inner portion only, of a textile 25 box toe piece, or "butter", preferably after it has been attached to the toe end of a cut-off vamp, with a substance which is liquid when hot, and stiffens when cool, so that its edge portion will be left unsaturated, or in 30 its ordinary condition. We accomplish this object, primarily, by providing an absorbent pad having a face of the size and shape of the portion to be saturated, saturating the pad with the stiffening substance while heated to a liquid state, and then pressing the pad onto said portion to be saturated. In 35 performing this operation with a simple pad, however, it was ascertained that the stiffening substance hardened so rapidly, 40 that it did not penetrate the cloth or canvas of which the tip piece was made, to an appreciable extent, but merely thinly coated its surface, so that sufficient material was not incorporated with the cloth to make it 45 as stiff as desired, when cold. It was further ascertained that the substance would accumulate on the pad each time it was used, so that the pad became thickly coated, and enlarged, and as the substance in the pad 50 soon hardened, the pad soon lost all of its absorbent qualities and became solid and unyielding.

A further object of our invention is to 55 obviate these difficulties, which object we have accomplished by providing a thin flat pad of suitable shape and so supported that

it may be conveniently used as a hand implement and by incorporating therewith a heating means, so arranged that the pad may be kept constantly heated, whereby the 60 saturating liquid contained in the pad, or carried thereby, cannot become cooled and harden, either within, or on the surface of the pad, and the portion of the cloth, to which the liquid is applied, will also be heated 65 by the pad, so that the liquid will be caused to flow completely through the cloth, without becoming cooled thereby, and the portion to which the pad is applied will become as thoroughly saturated as if it had 70 been dipped in a receptacle containing the heated liquid, while the adjacent portion will remain unsaturated.

An embodiment of means for performing this process, is illustrated in the accompanying drawing, in which:—

Figure 1 is a side elevation partly in section, of such means. Fig. 2 is a bottom plan view thereof. Fig. 3 is an edge view of the pad and its heating plate. Fig. 4 is a plan view thereof. Fig. 5 is a plan view of a tip 80 piece after saturation.

According to our invention, we provide a holder, or casing *a*, preferably composed of some light metal, as aluminum, the side 85 walls thereof being shaped to correspond to the outline of the portion of the tip piece which is to be saturated, and being provided with a recess *a'* in its under side. A flat pad *b*, of uniform thickness, is disposed in 90 said recess, said pad being preferably composed of felt or other highly absorbent material, and exactly corresponding, in contour, to the outline of the tip piece portion to be saturated. A brass plate *c* is attached 95 to the inner, or upper side of the pad, by threads *d*, passing through holes bored in the plate, or by other suitable means, said pad and plate being secured in the recess *a'* by means of a screw *d'*, and said plate being held against a transverse partition *a*² 100 in the casing, forming the bottom of said recess.

A chamber *a*³ is formed in the casing above the partition *a*², and an electric heater, 105 or heat unit *e* is arranged therein, so that it rests directly on the partition *a*², said chamber being filled with a packing of asbestos *f*, or other suitable material. A cover *g*, having a handle *h* connected thereto, is secured 110 to the upper end of the casing, a suitable heat insulating tube *i* being provided there-

between, and a flexible electric cable *j* is extended through the handle into the heat unit *e*, said cable being connected to a suitable source of electric supply. As thus arranged, when the electric current is turned on, the partition *a²* and the plate *c*, and also the side walls of the casing, will be heated by the electric heater *e*, and, as the pad *b* is of uniform thickness and is engaged 10 through its entire upper surface by said plate *c*, and at its edges by the casing walls, it becomes thoroughly and uniformly heated.

In using the device, the stiffening substance is heated in a suitable tank, so that 15 it is freely liquid, and then the protruding portion of the pad is dipped into the liquid, so that it becomes saturated therewith. The textile box-toe piece *x*, or "butter," having been previously connected to the tip end 20 of the leather vamp *y*, by sewing, as indicated in Fig. 5, in the usual manner, is then laid flat on a support, and the pad is pressed onto the toe piece *x* in such a position that 25 its nearly straight edge is in as close proximity to the end of the vamp *y* as possible, and its rounded edge is at a uniform distance from the edge of the toe piece, as indicated by the shaded area in Fig. 5. As the 30 pad is pressed against the textile toe piece, the heated liquid will be expressed from the pad, and will flow into and be absorbed by the toe piece, absorption thereby being made possible, because the portion thereof directly beneath the pad also becomes heated 35 by the heat from the pad, so that such portion becomes thoroughly saturated throughout its entire thickness. As only the textile portion, which is in direct contact with the pad, is heated, the liquid will not flow into 40 and saturate the adjacent portion thereof, this being prevented by the rapid cooling of the liquid, as it comes in contact with the unheated portion, so that practically only that portion of the tip piece to which the 45 pad is actually applied is saturated.

As the pad is at all times heated, while in use, to a sufficient temperature to maintain the stiffening material in a liquid state; this material will not accumulate thereon 50 and if the casing should happen to be dipped in the liquid, also, the material will be prevented from accumulating thereon, as the casing walls are heated to a point above the melting point of the material.

55 With the above described device, the operation of saturating the textile toe pieces may be rapidly performed, as the operator merely has to dip the pad in the liquid and press it against a piece for a short time, 60 and then the operation may be repeated on the next piece.

We claim:

1. A device for saturating a portion of an

absorbent sheet with a stiffening substance, which is liquid when heated above ordinary 65 temperatures, and hardens on cooling, composed of an absorbent pad having an engaging face shaped to correspond to the sheet portion to be saturated, and adapted to be pressed thereagainst, and means for heating 70 said pad to maintain the saturating substance therein in a liquid state.

2. An implement for saturating a portion of an absorbent sheet with a liquid substance which is self-hardening on cooling to ordinary 75 temperatures, composed of an absorbent pad having a sheet-portion engaging face at its under side, and means for heating said pad to maintain the substance absorbed thereby in a liquid state, and for 80 simultaneously pressing its face against the sheet-portion to be saturated, to heat said sheet-portion and deliver the liquid substance thereto.

3. An implement for saturating a portion 85 of an absorbent sheet, composed of a casing having a bottom recess, an absorbent pad located in said recess and projecting at its lower portion beyond the walls thereof, and having a work-engaging face on its under 90 side, and heating means for the pad located within the casing above and in proximity thereto, as, and for the purpose described.

4. A device for saturating a portion of an absorbent sheet, with a substance which is 95 liquid when hot, and a solid, or semi-solid, at ordinary temperatures, composed of a holder, an absorbent pad of approximately uniform thickness connected to the holder, and having a work-engaging face on its under side, a heat-conducting plate disposed in engagement with approximately the entire upper surface of the pad, and means for heating said plate to heat the pad to the liquefying temperature of the saturating 105 substance.

5. An implement for saturating a portion 110 of an absorbent sheet with a substance which is a solid, or semi-solid, at ordinary temperatures, and a liquid at higher temperatures, composed of a metallic casing having a recess in its under side, an absorbent pad disposed in and protruding from said recess, a heater disposed in said casing above the pad, means to conduct the heat from the 115 heater to the pad, and a handle connected to the casing.

In testimony whereof, we have signed our names to this specification, in the presence of two subscribing witnesses.
